UNITED STATES PATENT OFFICE.

SEGVART C. O. BERG, OF KANSAS CITY, MISSOURI.

BARREL-RINSER.

No. 867,568.

Specification of Letters Patent.

Patented Oct. 8, 1907.

Application filed August 12, 1907. Serial No. 388,176.

To all whom it may concern:

Be it known that I, SEGVART C. O. BERG, a citizen of the United States, residing at Kansas City, in the county of Jackson and State of Missouri, have invented 5 certain new and useful Improvements in Barrel-Rinsers, of which the following is a specification.

My invention relates to improvements in barrel-washers; and it provides for the alternate discharge of hot and cold water into barrels for the purpose of washing 10 and rinsing the same.

The invention consists of the novel construction, combination, and arrangement of parts hereinafter pointed out in the appended claims.

Referring now to the accompanying drawings which 15 illustrate the invention: Figure 1 represents a vertical section of the barrel-rinser on line I—I of Fig. 2. Fig. 2 is a vertical section of same on line II—II of Fig. 1. Fig. 3 is a cross section on line III—III of Fig. 1. Fig. 4 is a cross section on line IV—IV of Fig. 2.

20 1 designates an outer shell provided with a pair of supporting legs 2, a hot water inlet 3, a cold water inlet 4, a hot water outlet 5, and a cold water outlet 6, all of which are arranged as shown in Figs. 1 and 2. Said outer shell is open at its upper end to receive an inner 25 shell 7 having a chamber 8 and a duct 9 communicating with said chamber. The inner shell 7 consists of a disk 10, a partition 11, a marginal flange 12, and a tubular extension 13. Disk 10 is seated upon packing 14 in the lower portion of the outer shell. Flange 12 closes 30 the upper end of the outer shell to which it is secured by screws 15. Partition 11 divides the outer shell into chambers 16 17 communicating respectively with outlets 5 and 6.

18 designates a nozzle carried by extension 13 and 35 adapted to be inserted through the bung-hole of the barrel.

19 designates a saddle rotatably mounted upon the extension 13 and a circular seat 20 which latter is integral with the upper portion of flange 12, said saddle 40 being provided with a centrally-disposed hub 21 journaled upon extension 13 for the purpose of holding the saddle in place. The sides of the saddle are closed to form a basin 22, having a port 23 adapted to alternately communicate with ports 24 25 extending through flange 45 12 and communicating, respectively, with chambers 16 and 17. Hub 21 is provided with a cam 26, which alternately depresses two valves 27 28 which normally close two lower ports 29 30 communicating, respectively, with inlets 3 and 4 and chamber 8.

50 The upper ends of the valve-stems are provided with bearings 31 in which are journaled antifriction rollers 32, with which cam 26 alternately contacts, the rollers being prevented from turning at right angles to the cam by a pair of guides 33 depending from bearings 31 and 55 slidably arranged in flange 12 and the upper wall of

chamber 8. Bearings 31 operate in recesses 31^a provided in the upper portion of flange 12 for their reception.

The valves are rendered self-closing by expansion springs 34 embracing the valve-stems and abutting 60 against the top wall of chamber 8 and two transverse pins 35, which latter extend through the stems.

In practice a barrel is placed upon the saddle, care being taken to insert the nozzle through the bung-hole thereof, the barrel and the saddle are then rotated to 65 alternately bring cam 26 into contact with the antifriction rollers 32 for the purpose of alternately depressing the valves to open the ports 29 and 30. When port 29 is opened hot water from inlet 3 will enter chamber 8 and passing upwardly through duct 9 and nozzle 70 18 will be discharged with considerable force into the barrel, until cam 26 passes out of engagement with the antifriction roller of valve 27 and permits the same to close port 29.

While the hot water is discharging into the barrel, 75 port 23 is in coincidence with port 24 so that the water flowing from the barrel into the basin will pass through said ports into chamber 16 and thence out through the hot water outlet 5. As the barrel and the saddle continue to rotate, cam 26 will contact with the antifriction roller on valve 28 and depress the latter so that the cold water will pass up through port 30 into chamber 8 and thence through duct 9 and nozzle 18 to the barrel, at the same time port 23 is brought into coincidence with port 25 so that as the cold water discharges from 85 the barrel into the basin, it will flow from the latter through ports 23 and 25 into chamber 17 from which it escapes through the cold water outlet 6.

From the above description it will be understood that the hot and cold water will be kept separated by 90 partition 11 and through the alternate action of valves 27 28.

When the rinsers are connected in series, supply pipes are connected to both ends of the inlets 3 and 4, but when a single rinser is employed one end of each 95 inlet is closed with a plug.

Having thus described my invention, what I claim is:

1. A barrel-rinser consisting of an outer shell having two separated inlets and two outlets, an inner shell separating the outlets and provided with lower ports communicating with the inlets and upper ports communicating with the outlets, valves carried by the inner shell for normally closing the lower ports, a nozzle communicating with the inner shell, and a rotatable saddle adapted to alternately open the valves and provided with a port which 100 alternately communicates with the upper ports of the inner casing.

2. A barrel-rinser consisting of an outer shell having two separated inlets and two outlets, an inner shell having two lower ports communicating with the inlets and upper ports communicating with the outlets, a transverse partition on the inner shell separating the outlets, valves carried by the inner shell for normally closing the lower 105 110 ports.

- ports, a nozzle communicating with the inner shell, and a rotatable saddle adapted to alternately open the valves and provided with a port which alternately communicates with the upper ports of the inner casing.
5. 3. A barrel-rinser consisting of an outer shell having two separated inlets and two outlets, an inner shell separating the outlets and provided with lower ports communicating with the inlets and upper ports communicating with the outlets, self-closing valves carried by the inner shell for normally closing the lower ports, a nozzle communicating with the inner shell, and a rotatable saddle adapted to alternately open the valves and provided with a port which alternately communicates with the upper ports of the inner casing.
10. 4. A barrel-rinser consisting of an outer shell having separated inlets and outlets, an inner shell having lower ports communicating with the inlets and upper ports communicating with the outlets, valves carried by the inner shell for normally closing the lower ports, guides on said valves slidably arranged in the inner shell, a nozzle communicating with the inner shell, and a rotatable saddle on the inner shell having a cam which alternately opens the valves and a port which alternately communicates with the upper ports of the inner casing.
15. 5. A barrel-rinser consisting of an outer shell having separated inlets and outlets, an inner shell having lower ports communicating with the inlets and upper ports communicating with the outlets, valves carried by the inner shell for normally closing the lower ports, said valves being provided with antifriction rollers, a nozzle communicating with the inner shell, and a rotatable saddle on the inner shell having a cam which alternately contacts with the antifriction rollers, and a port which alternately communicates with the upper ports of the inner casing, said saddle having a basin communicating with its ports.
20. 6. A barrel-rinser consisting of an outer shell having two separated inlets and two outlets, an inner shell separating the outlets and provided with lower ports communicating with the inlets and upper ports communicating with the outlets, said inner shell being also provided with a tubular extension and a circular seat, valves carried by the inner shell for normally closing the lower ports, a nozzle communicating with the tubular extension, and a rotatable saddle adapted to alternately open the valves and provided with a port which alternately communicates with the upper ports of the inner casing.
25. In testimony whereof I affix my signature, in the presence of two witnesses.
- SEGVART C. O. BERG.
